UNITED STATES PATENT OFFICE.

WILLIAM H. BARR, OF CONWAY, MISSOURI.

FIRE-ESCAPE STEP-ROD ATTACHMENT.

SPECIFICATION forming part of Letters Patent No. 328,636, dated October 20, 1885.

Application filed July 30, 1884. Serial No. 139,207. (No model.)

To all whom it may concern:

Be it known that I, WILLIAM H. BARR, a citizen of the United States, residing at Conway, in the county of Laclede and State of Missouri, have invented certain new and useful Improvements in Fire-Escape Step-Rod Attachments, of which the following is a specification.

My invention relates to certain new and useful improvements in means for enabling persons to escape from a burning building; and the invention consists in the peculiar combinations and the construction and arrangement of parts hereinafter more fully described, and then specifically pointed out in the claims.

In the accompanying drawings, which form a part of this specification, Figure 1 is a perspective view of a building with my improvement applied thereto. Fig. 2 is a side elevation of one of the rods detached, and Fig. 3 is a sectional detail showing the manner of securing the rods in place.

Referring now to the details of the drawings, the letter A designates a rod, which is formed preferably of iron and of the form shown in the drawings. I usually make these rods about thirty inches long, with the ends B of such a length that when they are inserted in the wall of a building the rod will project about six inches from the wall; but I do not wish to limit myself to the exact dimensions of the

rods, as it is evident that the same may be varied without departing from the spirit of my invention.

The ends B of the rods A are provided with slots a, the object of which will soon be explained. In practice these rods A are driven or otherwise inserted into the wall of a building either to the right or left of a window, and preferably about twelve inches apart, and extend nearly to the ground. I also place two of them under each window, to aid and support the individual while coming out of the window. After these rods are driven into the wall a key, b, is inserted into the slots a of the projecting ends B, as clearly shown in Fig. 3, thus preventing the rods from being pulled out or working loose when any one is descending on them.

By my construction I provide a cheap, strong, and efficient means of escape in case of fire, and one that is very durable and always ready for use.

What I claim as new is—

The rods A, the projecting ends B of which are provided with slots a, in combination with the key b, adapted to engage with said slots, substantially as and for the purpose specified.

W. H. BARR.
